UNITED STATES PATENT OFFICE.

OTTO E. FISHBURN, OF NEW YORK, N. Y., ASSIGNOR TO GENERAL MOTORS CORPORATION, OF DETROIT, MICHIGAN, A CORPORATION OF DELAWARE.

OIL-PAN-SUPPORTING BRACKET FOR MOTOR VEHICLES.

Application filed December 15, 1919. Serial No. 344,905.

To all whom it may concern:

Be it known that I, OTTO E. FISHBURN, a citizen of the United States, and a resident of New York, county of New York, and 5 State of New York, have invented certain new and useful Improvements in Oil-Pan-Supporting Brackets for Motor Vehicles, of which the following is a full, clear, concise, and exact description, such as will enable others skilled in the art to which the 10 invention relates to make and use the same, reference being made therein to the accompanying drawings, which form a part of this specification.

15 My invention relates to motor propelled vehicles, and particularly to the frame thereof and to the manner in which various elements of the vehicle, regarded in its entirety, are supported from the said frame.

20 The principal object of my invention is to provide an improved scheme for supporting the oil pan commonly present in motor vehicles in place beneath the engine or motor of the vehicle, and from the frame thereof.

25 A further object of my invention is to provide an improved method of supporting the oil pan from the frame of the vehicle and in which a single fastening member such as a bolt or rivet performs two distinct 30 functions, one having to do with the supporting of the oil pan from the vehicle frame and the other with the securing of some other element of the vehicle to the said frame.

35 A further object of my invention is to provide an improved oil pan supporting bracket construction and arrangement, the bracket being secured to one of the side frame members of the vehicle frame and the features being such that the oil pan may be 40 readily assembled with and properly supported from the frame of the vehicle through the use of a plurality of brackets made in accordance with my invention.

45 Various other objects will appear from the following description wherein the preferred embodiment of my invention is described; altho it will be appreciated that my invention includes all such variations and modifications of the particular embodiment thereof 50 hereinafter described in detail and illustrated in the drawing accompanying and forming a part of this specification as come within the scope of the concluding claims, wherein the particular features in which my 55 invention consists are pointed out at length.

Referring now to the drawing wherein the preferred embodiment of my invention is illustrated:

Figure 1 is a perspective view showing the forward end of a motor vehicle frame, and 60 in which the oil pan and various elements of the vehicle are supported from the side frame members in accordance with my invention.

Figure 2 is a view showing a section on a 65 transverse plane indicated by the lines 2—2, Figure 1.

Figure 3 is a view showing a section upon a transverse plane indicated by the line 3—3, 70 Figure 1.

Figure 4 is a view showing a detail upon a larger scale.

Figure 5 is a view showing a section upon a plane corresponding with Figures 2 and 3 but showing certain elements of my invention 75 on a larger scale.

Referring to the drawing, the reference numerals 4, 5 designate the two side frame members of a motor vehicle frame; said members being illustrated as channel shaped 80 in cross-section and made up of upper and lower substantially horizontally-disposed flanges 6, 7, 8, 9, and vertically disposed webs 10, 11 extending between said flanges, as best shown in Figures 2 and 3. It will be 85 appreciated, however, that my invention regarded in its broader aspect is quite independent of the particular form of the frame members employed, and that the same is applicable to frame members of any of the 90 forms at present in use in motor vehicle construction.

The reference numerals 12 designate a plurality of oil pan supporting brackets secured to the side frame members 4, 5, and 95 which brackets serve as supports for an oil pan 13 located beneath the engine or motor of the vehicle and having a substantially horizontal flange at its upper edge extending beneath the side frames, and longitudinally 100 throughout such a length as may be necessary in order to catch such oil as may drip from the motor, the transmission mechanism, or other portions of the power plant of the vehicle.

105 These brackets are each shown as having a vertical portion or arm 14 extending upwardly and along the web portion of the side frame to which they are secured, and a substantially horizontal portion 15 extend-

100

105

110

ing along the lower of the two flanges of the side frame members; it being appreciated that all of the brackets are alike, so that a description of one of them will apply to all.

- 5 The oil pan supporting brackets are secured to the side members of the vehicle frame by means of fastening members such for example, as bolts or rivets extending 10 through holes provided in the vertical portions of the brackets and in the web of the side frames; and the fastening members whereby the brackets are secured to the frame members also serve in the case of 15 some or all of the brackets to fasten other elements of the vehicle to the side frame. Thus the reference numeral 16 designates one of two fender supporting arms, the lower ends 17 of which are secured to the 20 side frame members by means of fastening members 18 extending through holes provided in the vertical portions of the forward pair of brackets, and through holes in the webs of the frame members and also in the 25 lower ends of the supports 16; it being appreciated that a support similar to the one shown will be located upon the other side of the vehicle, and secured to the frame member 5. The fastening members 18 thus 30 form a double function in that they act to secure both the fender supports and the forward pair of brackets in place relative to the side frame members, thus avoiding the provision of holes in the side frame for the 35 reception of fastening bolts for the fender support in addition to holes for securing the oil pan supporting brackets in place; a single hole, or holes should additional security be required, thus serving to accommodate 40 the fastening members which secure both the members in question to the frame.

- In the same way fastening bolts or rivets 19 extend through a single hole or set of holes in the web of the frame, through holes 45 in the middle pair brackets, and through holes at the upper ends of running board supporting members 20 depending from the frame, a single fastening member or members thus serving to hold both a bracket and 50 the running board supporting member located adjacent and associated with it in place relative to the frame member; while the rearmost pair of brackets illustrated are secured in place and to the frame members 55 by fastening members 21 extending through holes provided in said brackets, through holes in the frame member, and through holes in bearing members 22, one only of which is shown, in which the ends of a 60 transversely extending brake operating or other shaft may be supported.

- It will of course be appreciated that if more brackets are necessary to support the oil pan than there are auxiliary elements to 65 be secured to the side frame members the

fastening bolts or rivets for the excess brackets will perform one function only, that is the function of securing the brackets to the frame members.

The lower horizontal portions 15 of the 70 brackets 12 extend beyond the free edges of the lower flanges 7, 8, and are provided with holes through which supporting members shown as in the form of bolts 23 extend; which bolts also extend through holes provided adjacent the side edges of the upper flange portion of the oil pan and are provided with nuts 24 at their lower ends, as shown in Figures 2 and 3, suitable washers 25 being ordinarily interposed between the 80 nuts and the oil pan. The side edges of the oil pan preferably extend beneath the flanges 7, 8 as shown and contact with the undersides of said flanges.

The fastening bolts 23 are preferably provided with nuts 26 which are prevented from turning by the adjacent side edges of the lower frame flanges, from which it follows that in assembling the brackets with the frame the bolts 23 may be screwed 90 through the nuts 26, and the nuts drawn tightly against the undersides of the horizontal portions 15 of the brackets; thus providing downwardly extending stationary threaded studs and enabling the oil pan to be 95 put in place from beneath and moved upward and into engagement with the studs, and then secured by screwing the nuts 24 in place, or removed by a reverse operation, without in either case actually removing the 100 bolts from the brackets. Lock washers 27 are commonly interposed between the heads of the bolts and the upper surfaces of the horizontal portions of the brackets to thereby prevent the bolts from unscrewing after 105 the nut 26 has been drawn into firm contact with the undersides of the lower arms of the brackets.

Having thus described and explained my invention, I claim and desire to secure by 110 Letters Patent:

1. In a motor vehicle, a side frame member having upper and lower substantially horizontal flanges, and a vertically disposed web connecting said flanges; an oil pan supporting bracket having a horizontally disposed portion extending along the upper side of the lower of said flanges and beyond the edge thereof; a fastening member whereby said bracket is secured to said frame member; an oil pan supporting bolt extending through a hole provided in the free end of the horizontal portion of said bracket; and a nut through which said bolt extends, and the periphery of which engages the free 120 edge of said lowermost horizontal flange.

2. In a motor vehicle, a frame member having a flange; a bracket secured to said member and having a portion extending beyond the edge of said flange; a bolt carried 130

by the said extending portion of the bracket; an oil pan supported upon the bolt; and a combined spacing and securing means mounted upon said bolt between the pan and 5 the bracket and adapted to prevent displacement of the bolt from the bracket during the normal operation of removing and replacing the oil pan.

3. In a motor vehicle, a side frame member having upper and lower substantially horizontal flanges, and a vertically disposed web connecting said flanges; an oil pan supporting bracket having a horizontally disposed portion extending along the upper 10 side of the lower of said flanges and beyond the edge thereof; a fastening member whereby said bracket is secured to said frame member; an oil pan the side edge of the upper end of which extends beneath the 15 lower of the flanges aforesaid and which oil pan is movable as a unitary structure downward without interference by said frame member; an oil pan supporting bolt extending through holes provided in the free end 20 of the horizontal portion of said supporting bracket beyond the free edge thereof and in said oil pan, and a nut through which said bolt extends, and the periphery of which engages the free edge of said lowermost 25 horizontal flange.

4. In a motor vehicle, a side frame member having upper and lower substantially

horizontal flanges, and a vertically disposed web connecting said flanges; an oil pan supporting bracket having a horizontally disposed portion extending along the upper side of the lower of said flanges and beyond the edge thereof, and a vertical extending portion; a fastening member extending through holes in said vertically extending 35 portion and in said web; an oil pan supporting bolt extending through a hole provided at the free end of the horizontal portion of said bracket; a nut through which said bolt extends and the periphery of which engages 40 the free edge of said lowermost horizontal flange; and an oil pan having an opening adjacent its free side edge and through which said oil pan supporting bolt extends to thereby support said pan. 50

5. In a motor vehicle, a side frame member having a lower substantially horizontal flange, and a web; an oil pan supporting bracket secured to said web and extending along the upper side of said flange and beyond the free edge thereof and provided with a hole adjacent its free end; an oil pan supporting bolt extending downwardly through the hole aforesaid; and a nut through which said bolt extends and which 55 nut engages the edge of said flange to thereby prevent it from rotating upon said bolt. 60

In testimony whereof I affix my signature:
OTTO E. FISHBURN.
